US0D1077639S

(12) **United States Design Patent** (10) **Patent No.:** **US D1,077,639 S**
(45) **Date of Patent:** **** Jun. 3, 2025**

(54) **BOTTLE**

(71) Applicant: **The Procter & Gamble Company**,
Cincinnati, OH (US)

(72) Inventors: **Kenneth Shun Qiang Ang**, Singapore
(SG); **Yilin Hong**, Beijing (CN)

(73) Assignee: **The Procter & Gamble Company**,
Cincinnati, OH (US)

(**) Term: **15 Years**

(21) Appl. No.: **29/876,963**

(22) Filed: **May 31, 2023**

(30) **Foreign Application Priority Data**

Dec. 2, 2022 (WO) WIPO125848

(51) **LOC (15) Cl.** **09-01**

(57) **CLAIM**

The ornamental design for a bottle, as shown and described.

DESCRIPTION

FIG. 1 is a perspective view of a bottle;

FIG. 2 is a front view of the bottle of FIG. 1;

FIG. 3 is a right side view of the bottle of FIG. 1;

FIG. 4 is a back view of the bottle of FIG. 1;

FIG. 5 is a left side view of the bottle of FIG. 1;

FIG. 6 is a top view of the bottle of FIG. 1; and,

FIG. 7 is a bottom view of the bottle of FIG. 1.

In the drawings, the broken lines show portions of a bottle
that form no part of the claim.

1 Claim, 4 Drawing Sheets
